UNITED STATES PATENT OFFICE.

LAURENCE S. BARLOW AND ROBERT JOHN RICHARDSON, OF LOS ANGELES, CALIFORNIA.

DESIGN FOR AN ORANGE-PEELER.

49,638.

Specification for Design.

Patented Sept. 12, 1916.

Application filed May 1, 1916. Serial No. 94,839. Term of patent 7 years.

To all whom it may concern:

Be it known that we, LAURENCE S. BARLOW and ROBERT J. RICHARDSON, subjects of the King of Great Britain, and residents of Los Angeles, county of Los Angeles, State of California, have invented a new, original, and ornamental Design for Orange-Peelers, of which the following is a specification, reference being had to the accompanying drawings, forming a part thereof.

We claim:

The ornamental design for an orange peeler as shown.

LAURENCE S. BARLOW.
ROBT. JOHN RICHARDSON.
